UNITED STATES PATENT OFFICE.

MILTON TIBBETTS, OF DETROIT, MICHIGAN, ASSIGNOR TO PACKARD MOTOR CAR COMPANY, OF DETROIT, MICHIGAN, A CORPORATION OF MICHIGAN.

IGNITION APPARATUS FOR HYDROCARBON-ENGINES.

1,227,697.

Specification of Letters Patent.

Patented May 29, 1917.

Application filed February 19, 1910. Serial No. 544,822.

To all whom it may concern:

Be it known that I, MILTON TIBBETTS, a citizen of the United States, and resident of Detroit, county of Wayne, State of Michigan, have invented certain new and useful Improvements in Ignition Apparatus for Hydrocarbon-Engines, of which the following is a specification.

This invention relates to ignition apparatus for hydrocarbon engines, and particularly to ignition apparatus for the engines of motor vehicles, although some of the features are not limited to this particular application.

15 The ignition apparatus of a motor vehicle is generally placed in a receptacle which is mounted on the dash of the motor vehicle. In view of the fact that a hood sometimes extends rearwardly over the dash, it is difficult to remove the apparatus from the receptacle since the hood interferes. It is generally necessary to remove the entire receptacle from the dash so that the apparatus may be removed therefrom.

20 25 One of the objects of this invention is to support the receptacle in such a manner that it may be moved to a position to clear the hood so that the apparatus may be readily removed.

25 30 Another object is to support the conductors and connections for the apparatus in such a manner that they will be efficiently insulated.

Another object is to improve the apparatus and receptacle in general.

Further objects will appear from the detailed description.

The invention will be described in connection with the accompanying drawings, in which:

Figure 1 is a section on the line 1—1 Fig. 2, parts of the apparatus being shown in elevation;

Fig. 2 is a section on the line 2—2 Fig. 4;

Fig. 3 is a section on the line 3—3 Fig. 2;

Fig. 4 is a bottom view, the dash being shown in section;

Fig. 5 is a front elevation;

Fig. 6 is an elevation showing another form of this invention;

Fig. 7 is a section on the line 7—7 Fig. 6;

Fig. 8 is a section on the line 8—8 Fig. 9, showing another form of this invention;

Fig. 9 is an elevation partly in section of the form shown in Fig. 8;

Fig. 10 is a section on the line 10—10 Fig. 9.

Referring to Figs. 1 to 5, 15 designates the dash of a motor vehicle, and 16 the overhanging hood. A receptacle 17 is pivotally supported, in a manner hereinafter described in detail, on brackets 18 and 19 secured to the dash, so that the receptacle may swing from full to dotted line position shown in Fig. 2. The receptacle is arranged to receive and support the usual ignition apparatus consisting of trembler coil 20 and transformer coil 21. The bottom wall of the receptacle is arranged to support a series of contacts 22, 23, 24, 25 and 26 and 65 the coils are removably supported in the receptacle and provided with a series of contacts coöperating with the contacts 22 to 26, inclusive, this particular construction being shown and described in patent to Huff 75 838,251, granted December 11, 1906. As described in said patent, and as shown in Fig. 3, the contacts 22 and 23 connect with the high tension terminals of the coils, the contact 24 connects with the joined high and 80 low tension terminals of the coils, and the contacts 25 and 26 connect with the other low tension terminals of the coils.

The contact 24 is connected with a brush 24^a and with a metallic bracket 27, secured 85 to the bottom wall of the receptacle, by conductors indicated at 24^b in Fig. 1. A rotatable switch 29 is supported in the bracket 27 and another bracket 28, also mounted on and secured to the wall of the receptacle. 90 This switch comprises a cylinder of insulating material provided with contact segments 30, 31 and 32. A pair of brushes 33^a and 34^a are supported on a bracket 35, (Fig. 2) which is mounted upon the dash of the 95 vehicle. These brushes are electrically con-

ected to the battery 33 and the magneto 34 by conductors 33^b and 34^b, respectively, passing through and supported by the bracket 35. Brushes 25^a, 26^a, 22^a and 23^a are supported from the bottom wall of the receptacle, and are arranged to bear upon the rotary switch 29. As shown in Fig. 3, the brushes 25^a and 26^a are electrically connected to the contacts 25 and 26, respectively, while the brushes 22^a and 23^a are electrically connected to the contacts 22 and 23 respectively. The arrangement of the brushes and their relative positions with respect to the contact segments on the switch is shown in Figs. 1 and 4. A pivot pin 27^a, for switch 29, is provided with a flange which constantly bears on and has an electrical connection with the metallic bracket 27. This pivot is mounted in a metallic bearing 36 of the bracket 18, which is of insulating material. The segment 32 is provided with an extension 38 forming a pivot, which is mounted in a bearing 38^a of conducting material. The bearing members 36 and 38^a have similar extensions through brackets 18 and 19, the extension on member 38^a appearing in Fig. 2. The bearing member 38^a is electrically connected to a distributor 40 by means of a suitable conductor 39. The connection between the parts 39 and 38^a is preferably made by a plug switch arrangement 41, and the connection between the conductor 37, which is grounded and the member 36 is made by a similar plug switch 41^a. The distributor 40 is arranged to successively connect the spark plugs *x* of the hydrocarbon engine cylinders in a manner well known to those skilled in the art. In this particular embodiment, the invention is shown as applied to a four cylinder engine and the relative position of the distributor is shown in the diagrammatic portion of Fig. 2.

The switch 29 has secured thereto a toothed segment 42, which is arranged to mesh with a rack 43 guided in the front wall of the receptacle. The rack is operated by means of a button 44, the shank of which works in a slot 46 in a plate 50. The slot (see Fig. 5) is provided at its ends with depressions 47 and at an intermediate point with another notch or depression, all three of said depressions being adapted to receive the shank of the button which is provided with a spring 45, so as to latch the button and rack in the different positions. The button has formed thereon a lug 48, which is arranged to be engaged by the bolt of a lock 49.

The receptacle 17 is normally secured in place against the dash by means of the clamping nuts 52 and brackets 51. When it is desired to remove or replace the coils in the receptacle, the clamping nuts are loos-

ened and the receptacle swung about the 65 pivots 27^a and 38 to dotted line position shown in Fig. 2. In this position the top of the receptacle will clear the hood 16 and, therefore, the coils may be readily removed. It will be noted that the pivots 27^a and 38 70 are so arranged relatively to the receptacle 17 that the center of gravity of the receptacle will fall rearwardly and forwardly of the pivots when the receptacle is in the different positions shown in Fig. 2. 75

The operation of the switch 29 is similar to that shown in the Patent No. 838,251 referred to.

In order to connect the magneto in circuit, the button 44 is moved downwardly to 80 the lower depression 47 or to "Mag" position. This will move the rack 43 downward, thus rotating the toothed segment 42 and thereby turning the switch 29, so that the segment 30 will be in a position to connect 85 the brushes 26^a and 34^a, which are side by side as shown in Fig. 4. At the same time the segment 32 will be moved into contact with brush 23^a (Figs. 1, 2 and 4). The low-tension current will then pass from the magneto by means of connection 34^b to brush 34^a, then through segment 30, brush 26^a to contact 26, which connects to the primary of the transformer, contact 24, connection 24^b to bearing 36, plug 41^a and connection 37 to 90 ground. The high tension circuit will be made through the spark plugs, distributor 40, connection 39, bearing member 38^a, pivot 38, segment 32, brush 23^a, contact 23, the secondary of the transformer, contact 24, connection 24^b, bracket 27, bearing 36, plug 41^a, connection 37 to ground. 95

In order to throw the battery in circuit, the button 44 is moved to cause its shank to enter the upper notch 47 or to "Bat" position. Through rack 43 and toothed segment 42, this will rotate the switch 29 to cause the segment 30 to connect brushes 33^a and 25^a (Fig. 4) and turn segment 32 into position to contact with brush 22^a. The connections may be traced in a manner similar to that for the magneto connections. When the battery is in circuit the segment 31 (Fig. 1) will connect the brushes 34^a and 24^a (Fig. 4) so that the magneto is short-circuited. That is, the circuit for the magneto will be from magneto by connection 34^b to brush 34^a, segment 31, brush 24^a, connection 24^b, bracket 27, to bearing 36, plug 41^a, connection 37 to ground. 110

In order to throw the switch to neutral position the button 44 is moved to bring its shank into the intermediate notch or depression or to "off" position. This will disconnect both the battery and the magneto and will also break the high tension connections, the magneto remaining short-circuited through the brushes 34^a and 24^a and segment 115 120

- 31, this segment subtending a greater angle than the other segments, so that it remains in contact with the brushes 34^a and 24^a whether the switch button 44 is in "Bat" or 5 "off" position.
- The segments 30, 31 and 32 are made long enough so that the connections of the apparatus will remain undisturbed—that is, the segments will remain in contact with the 10 brushes with which they are engaged during the movements of the receptacle to operative and inoperative positions. It will be noted that the movement at the circumference of the switch will be relatively small.
- 15 By placing the switch outside of the box the coils can be placed close together, so that the size of the receptacle is very much reduced. The plate 50, which extends downwardly from the receptacle, forms a protective covering for the switch mechanism located below the receptacle. It is obvious 20 that the receptacle may be extended downwardly so as to cover the switch at the sides and bottom as well as at the end.
- 25 The high tension connections, which require the most careful insulation due to the high voltage and due to the fact that one of the high tension terminals is grounded, are mounted in the brackets so that they may be 30 carefully insulated from the ground—that is, from the motor frame. The entire high tension circuit is thus so designed that the insulation will be a maximum. The low tension terminals are mounted in a separate 35 bracket which enables the connections to be conveniently made, and which keeps the low tension wires at a safe distance from the high tension wires so that they may be thoroughly insulated from each other.
- 40 In the construction shown in Fig. 1, the brackets are shown as mounted upon and secured to the dash. These brackets may, however, be mounted upon a subbase, which 45 subbase is secured to the dash. The individual brackets form in fact together, one bracket having a plurality of bracket arms.
- 50 Another form of this invention is shown in Figs. 6 and 7. In this form the receptacle is mounted so as to swing on a vertical 55 axis. The brackets 18 and 19 are secured to the dash as in the construction shown in Fig. 1, and the receptacle is mounted upon these brackets through the medium of the rotatable switch 29. In this construction, 60 however, the bracket 35^a, which carries the low tension wires and brushes, is secured to the receptacle as shown in Fig. 6. The receptacle swings about a vertical axis away from the dash so that the coils may be readily removed when said receptacle 17 is in the dotted line position shown in Fig. 7. The receptacle is secured in operative position against the dash by means of a clamping nut 60, engaging a slotted bracket 61 on

the dash. The apparatus is otherwise of the 65 same construction as that shown in Figs. 1 to 5 inclusive.

Another form of this invention is shown in Figs. 8, 9 and 10. The arrangement of the coils and switch in this form is similar 70 to that shown in Patent No. 838,251 referred to, and therefore corresponding parts have been given the reference characters of parts in the above patent with an exponent added.

The receptacle 70 has mounted therein a 75 transformer coil 2^a and a trembler coil 3^a. A bracket 71 of insulating material is suitably secured to the receptacle and supports the switch 17^b. A downwardly extending portion 71' of the bracket 71 (see Fig. 10) 80 has secured thereto a plurality of L-shaped members 72 and 73, which have formed thereon trunnions 74 and 75 which engage bearings in a bracket 76. The L-shaped members 72 and 73 are of metal, while the bracket 76 is of insulating material. The switch 17^b is provided with segments 23^b and 27^b, which engage brushes which are mounted upon the bracket 71. The brushes are arranged in the same manner as shown 85 in Patent 838,251 referred to. A suitable connection 25^b is made from a binding post 77 to a suitable battery brush which bears on the switch and a connection 26^b is made from the binding post 78 to a suitable magneto brush which bears on the switch. Connections are made from the binding posts 77 and 78 to suitable spring contacts 79 and 80 engaging coöperating 90 contacts 81 and 82 respectively, the spring contact 79 being mounted on the portion 71' of the bracket while the coöperating contacts 81 and 82 are mounted on the bracket 76. The contacts 81 and 82 are 95 arranged to be connected to the battery and magneto respectively as indicated in Fig. 10. An electrical connection extends from the binding post 84 on the L-shaped member 73, Fig. 8, to the contact member 18^b, Fig. 9, while the ground connection is made to the binding post 83 on the L-shaped member 72. A binding post 85 for the ground connection is mounted on the bracket 76 and the shank of the binding 100 post is arranged to make an electrical connection with the trunnion 74. Similarly the binding post 86 for the distributor is arranged to have an electrical connection with the trunnion 75. The electrical connections between the trunnions and the binding posts may be made in any suitable 105 manner.

110 It will be seen that binding posts 77, 78, 83 and 84 form what may be termed a connecting board. In order that these binding posts may be accessible, the front of the receptacle is provided with a removable plate 87 which is secured to the receptacle 115 120 125

by one or more screws 88. A handle 89 is pivotally mounted on the casing and connected to the switch as in the patent referred to. In the construction shown, the 5 handle is mounted in a bearing aperture in the plate 87, a flange 89^a forming a stop to hold it in position. This handle is arranged to be locked in "off" position by means of a lock 90, the handle having a 10 key hole which registers with the key hole in the lock when the handle is in "off" position. The handle has a downwardly projecting portion 91 which covers the head of the screw 88. By means of the 15 above construction when the plate is in place and the handle 89 is locked, the extension 91 will cover the head of the screw 88, and thus will prevent removal of the plate 87 so that the connecting board can- 20 not be tampered with.

The receptacle swings about the trunnions 74 and 75 as an axis, and is locked in position by means of clamping nuts 93 engaging the slotted brackets 92. The 25 lower end of the receptacle is cut away as at 94, so that the receptacle may be placed in position between its trunnions on the bracket 76. It will be noted that the bracket 76 extends into the receptacle.

30 It is obvious that various changes may be made in the details of construction without departing from this invention, and it is, therefore, to be understood that this invention is not to be limited to the specific 35 construction shown and described.

Having thus described the invention, what is claimed is:

1. In a motor vehicle, the combination with the dash and ignition apparatus, of a 40 receptacle for the ignition apparatus, and means including a pivot for supporting said receptacle and constructed to permit it to be tilted from an upright to an inclined position, said supporting means being constructed so that the center of gravity of said receptacle will fall forwardly and rearwardly of said pivot when said receptacle is in operative and inoperative 45 positions respectively.

50 2. In a motor vehicle, the combination with the dash and ignition apparatus, of a receptacle for the ignition apparatus, means for supporting said receptacle, said means being constructed to permit said 55 receptacle to be moved rearwardly from the dash, and electrical connections for said apparatus made through said supporting means.

3. In a motor vehicle, the combination 60 with the dash and ignition apparatus, of a receptacle for the ignition apparatus, means for supporting said receptacle, said means being constructed to permit said receptacle to be moved rearwardly from the

dash, and high tension electrical connections for said apparatus made through said supporting means.

4. In a motor vehicle, the combination with the dash and ignition apparatus, of a receptacle for the ignition apparatus, a 70 bracket for supporting said receptacle, said bracket being constructed to permit said receptacle to be moved rearwardly from the dash, and electrical connections for said apparatus supported by said bracket.

5. In a motor vehicle, the combination with the dash and ignition apparatus, of a receptacle for the ignition apparatus, a bracket for supporting said receptacle, said bracket being constructed to permit said receptacle to be moved rearwardly from the dash, and high tension electrical connections for said apparatus supported by said bracket.

6. In a motor vehicle, the combination with the dash and ignition apparatus, of a receptacle for the ignition apparatus, a bracket for supporting said receptacle, said bracket being constructed to permit said receptacle to be moved rearwardly from the 90 dash, electrical connections supported by said bracket, electrical connections for said apparatus supported by said receptacle and a sliding engagement between said connections.

7. In a motor vehicle, the combination with the dash and ignition apparatus, of a receptacle for the ignition apparatus, a bracket for supporting said receptacle, said bracket being constructed to permit said receptacle to be moved rearwardly from the 100 dash, electrical connections supported by said bracket, electrical connections for said apparatus supported by said receptacle, said connections remaining undisturbed during the movements of said receptacle.

8. In a motor vehicle, the combination with the dash and ignition apparatus, of a 110 receptacle for the ignition apparatus, means for supporting said receptacle, said means being constructed to permit said receptacle to be moved rearwardly from the dash, electrical connections supported by said dash, 115 electrical connections for said apparatus supported by said receptacle, and a sliding engagement between said connections.

9. In a motor vehicle, the combination with the dash and ignition apparatus, of a receptacle for the ignition apparatus, means including a pivot connection for supporting said receptacle, said means being constructed to permit said receptacle to be swung rearwardly from said dash, and electrical connections to said apparatus made through 120 said pivotal connection.

10. In a motor vehicle, the combination with the dash and ignition apparatus, of a

- receptacle for the ignition apparatus, means including a pivotal connection for supporting said receptacle, said means being constructed to permit said receptacle to be 5 65 swung rearwardly from said dash, and high tension electrical connections to said apparatus made through said pivotal connection.
11. In a motor vehicle, the combination with the dash and ignition apparatus, of a receptacle for the ignition apparatus, a bracket, a pivotal connection between said bracket and receptacle whereby said receptacle may be swung rearwardly from said 10 70 dash, and electrical connections to said apparatus made through said pivotal connection.
12. In a motor vehicle, the combination with the dash and ignition apparatus, of a receptacle for the ignition apparatus, a bracket, a conducting bearing in said bracket, a conducting pivot on said receptacle and mounted in said bearing, and an electrical connection from said pivot to said 15 75 apparatus.
13. In a motor vehicle, the combination with the dash and ignition apparatus, of a receptacle for the ignition apparatus, a bracket secured to said dash, a conducting bearing in said bracket, a conducting pivot on said receptacle and mounted in said bearing, an electrical connection from said pivot to said apparatus, and electrical connections from said bearing to the forward 20 80 side of said dash.
14. In a motor vehicle, the combination with the dash and ignition apparatus, of a receptacle for the ignition apparatus, a bracket secured to said dash, a conducting bearing in said bracket, a conducting support on said receptacle movably mounted in said bearing, and constructed to permit said receptacle to be moved rearwardly of said dash, electrical connections from said 25 85 pivot to said apparatus, and electrical connections from said bearing to the forward side of said dash.
15. In a motor vehicle, the combination with the dash and ignition apparatus, of a receptacle for the ignition apparatus, and means including a switch for said apparatus supporting said receptacle, said means being constructed to permit said receptacle to be moved rearwardly from the dash. 30 90
16. In a motor vehicle, the combination with the dash and ignition apparatus, of a receptacle for the ignition apparatus, a bracket, and a switch for said apparatus secured to said receptacle and having engagement with said bracket, said bracket and switch being constructed to permit said receptacle to be moved rearwardly from the dash. 35 95
17. In a motor vehicle, the combination with the dash and ignition apparatus, means for supporting said receptacle, said means being constructed to permit said receptacle to be moved rearwardly from the dash, a switch for said apparatus, said switch being mounted on said receptacle and provided with contacts, a bracket, and contacts on said bracket engaging the switch contacts. 40 100
18. In a motor vehicle, the combination with the dash and ignition apparatus, of a receptacle for the ignition apparatus, means for supporting said receptacle, said means being constructed to permit said receptacle to be moved rearwardly from the dash, a rotatable switch for said apparatus, said switch being mounted on said receptacle and provided with contact segments, a bracket, and brushes on said bracket engaging said segments. 45 105
19. In a motor vehicle, the combination with the dash and ignition apparatus, of a receptacle for the ignition apparatus, a bracket on said dash constructed to support said receptacle and permit it to be moved rearwardly from the dash, a switch for said apparatus, said switch being provided with contacts, and a bracket on the dash provided with contacts engaging the switch contacts. 50 110
20. In a motor vehicle, the combination with the dash and ignition apparatus, of a receptacle for the ignition apparatus, a bracket constructed to support said receptacle and permit it to be moved rearwardly from the dash, an additional bracket, and electrical connections for said apparatus supported by said brackets. 55 115
21. In a motor vehicle, the combination with the dash and ignition apparatus, of a receptacle for the ignition apparatus, a bracket constructed to support said receptacle and permit it to be moved rearwardly from the dash, an additional bracket, and electrical connections for said apparatus supported by said brackets, said connections remaining undisturbed during the movements of said receptacle. 60 120
22. In a motor vehicle, the combination with the dash and ignition apparatus, of a receptacle for the ignition apparatus, a plurality of brackets, means for supporting said receptacle on a pair of said brackets, said means being constructed to permit said receptacle to be moved rearwardly from the dash, and high tension electrical connections from said apparatus supported by a pair of said brackets. 65 125
23. In a motor vehicle, the combination with the dash and ignition apparatus, of a receptacle for the ignition apparatus, a plurality of brackets, means for supporting said receptacle on a pair of said brackets,

- 5 said means being constructed to permit said receptacle to be moved rearwardly from the dash, high tension electrical connections for said apparatus supported by a pair of said 5 brackets, and low tension electrical connections from said apparatus supported by another of said brackets.
- 10 24. In a motor vehicle, the combination with the dash and ignition apparatus, of a receptacle for the ignition apparatus, a pair of brackets, means on said brackets for supporting said receptacle, said means being constructed to permit said receptacle to be moved rearwardly from the dash, high tension 15 electrical connections supported by said brackets, a bracket intermediate said brackets, and low tension electrical connections supported by said intermediate bracket.
- 20 25. In a motor vehicle, the combination with the dash and ignition apparatus, of a receptacle, a spark coil within said receptacle, a switch for completing the circuits of said coil, a bracket for supporting said receptacle constructed to permit it to be moved rearwardly from the dash, means for mounting said switch on one of the outside walls of said receptacle, and a protecting plate for said switch secured to said receptacle.
- 25 30 26. In a motor vehicle, the combination with the dash and ignition apparatus, of a receptacle for the ignition apparatus, a bracket extending into the receptacle, and means on the bracket and in the receptacle 35 constructed to permit said receptacle to be moved rearwardly from the dash.
- 40 27. In a motor vehicle, the combination with the dash, of an ignition apparatus comprising a receptacle, a spark coil in said receptacle, a switch for completing the circuit of said coil, a base for supporting said switch, a bracket, and means pivotally connecting said bracket and base and adapted to permit the receptacle to be moved rearwardly from the dash.
- 45 28. In a motor vehicle, the combination with the dash and ignition apparatus, of a receptacle for the ignition apparatus, trunnions for supporting said receptacle 50 constructed to permit it to swing away from the dash, and electrical connections made through said trunnions.
29. In a motor vehicle, the combination with the dash and ignition apparatus, of a receptacle for the ignition apparatus, a bracket, trunnions secured to said receptacle and journaled in said bracket at points within the receptacle, said parts being constructed to permit said receptacle to swing away from the dash of the vehicle. 60
30. In a motor vehicle, the combination with a dash and ignition apparatus, of a receptacle for the ignition apparatus, a bracket, means for supporting said receptacle on said bracket constructed to permit 65 said receptacle to move rearwardly of the dash, and means whereby placing said receptacle in position on the bracket makes the electrical connections.
31. In a motor vehicle, the combination with the dash and ignition apparatus, of a receptacle for the ignition apparatus, a bracket, means for supporting said receptacle on said bracket constructed to permit 70 said receptacle to move rearwardly of the dash, and coöperating high and low tension contacts on said receptacle and bracket, whereby electrical connections are made when said receptacle is placed in position in its bracket. 75
32. In a motor vehicle, the combination with the dash and ignition apparatus, of a receptacle for the ignition apparatus, a bracket for supporting said receptacle, coöperating contacts on said receptacle and 80 bracket, whereby electrical connections are made when said receptacle is placed in position in its bracket. 85
33. The combination of a receptacle and a bracket, means for pivotally supporting 90 said receptacle on said bracket, the center of gravity of said receptacle positioned above and on one side of the axis of the pivot when the receptacle is in a substantially upright position, and on the other 95 side of the axis when the receptacle is rotated on its pivot.

In testimony whereof I affix my signature in presence of two witnesses.

MILTON TIBBETTS.
